PULVERIZATION

Martin Frisch, New York, N. Y., assignor to Foster Wheeler Corporation, New York, N. Y., a corporation of New York

Application March 30, 1932, Serial No. 601,915

5 Claims. (Cl. 83—9)

My invention relates to pulverizing mills and more particularly to classifiers used with air-swept mills for separating and returning relatively coarse material to the mill. Still more particularly, my invention relates to classification in connection with mills of the ball type.

The primary object of my invention is to provide a classifier for effectively and regulatably separating the relatively coarse particles of material drawn from the mill by a current of air, and to provide means for returning the separated coarse material directly to the mill for further pulverization.

The usual arrangement of a suction fan between a ball mill and a classifier mounted above the mill is unsatisfactory because the coarse particles entering the fan will rapidly wear out the fan blades. On the other hand if the suction fan is placed beyond the classifier and the classifier is remote from the mill, the conduit between the classifier and mill is likely to become obstructed to some extent by coarse particles that are too heavy to be floated to the classifier and returned by gravity to the mill. It is a further object of my invention to overcome the above difficulties by locating the classifier directly at the outlet of the pulverizing mill so that the coarse particles or oversize do not reach the suction fan and cannot obstruct the passage of the finely pulverized material on its way to a point of use or storage. This is of particular advantage in connection with ball mills, as will be clear from the following description. My novel combination of classifier and ball mill provides a simpler and more efficient apparatus than previously known arrangements of similar kind.

Other objects and advantages of my invention will be apparent from the following detailed description of preferred embodiments thereof as illustrated in the accompanying drawing, of which:

Fig. 1 is a vertical cross-sectional view of a ball mill and classifier embodying the invention;

Fig. 2 is a cross-sectional view of the classifier, taken on line 2—2 of Fig. 1; and

Fig. 3 is a vertical cross-sectional view showing a modified classifier construction.

The ball mill 10 is provided at each end with hollow trunnions 11 and 12 which are journaled in the supporting brackets 13 and 14. The mill is rotated by the ring gear 15 mounted upon the cone-shaped portion of the casing 16 of the ball mill.

55 The material to be pulverized is fed to the mill

from any suitable feeder by means of the conduit 17 and chute 17'. The air employed in sweeping the pulverized material from the mill enters through conduit 18 and passes through a receptacle 19 associated with the hollow trunnion 12. An adjustable slide door or valve member 20 may be opened to supply additional air for sweeping the mill when desirable.

Extending into the hollow trunnion 11 is the inlet connection 21 to the classifier casing 22. Casing 22 of the classifier is supported by brackets 23 and 24 bolted to the foundation 25. A conduit 26 is connected to a suction fan F from which the mixture of air and pulverized material is fed directly to a furnace or conducted to a separator or a storage system, as desired. In the upper central portion of the casing 22 of the classifier is the deflecting plate or baffle 27 which may be adjusted from the outside by means of the wing nut 28. In the lower central portion of the classifier is the stationary curved baffle 29 and associated therewith is a curved deflecting plate 30 guided close to plate 29 and which may be adjusted by rotating shaft 31 having levers 32 mounted thereon, to which plate 30 is attached. An external hand lever 42 and clamping nut 43 are provided to rotate shaft 31 and fix the position of baffle 30. The arrows indicate the path of the mixture over the baffles and deflecting plates which may be generally described as being in the form of an S.

A screw conveyer 33 arranged in trough 33' is driven through gears 34 and 35 by means of a universal shaft coupling 36 and spider connection 37 attached to the rotating casing 16. The gears 34 and 35 are covered by a housing 38. A wire screen 39 of large mesh is arranged to cover the screw conveyer and extends from baffle 29 to the outlet 40 of the screw conveyer. The mesh of screen 39 is large enough, say $\frac{3}{4}$ inch, to permit coarse particles to pass downwardly therethrough onto the screw conveyer while preventing the passage therethrough of grinding balls or large sticks of wood.

The modification shown in Fig. 3 is similar to the construction shown by Fig. 1 except that the arrangement of deflecting plates is different. A flat baffle 41 extends in a slanting direction across the chamber formed by casing 22. At the top of the chamber is the deflecting plate 42 which may be adjusted to different positions.

The operation of the apparatus is as follows:

Material to be pulverized, which in the present case may be coal, is fed to the mill through chute 17' to the rotating hollow trunnion 12 into the

presence of grinding balls within the rotatable drum. The fan F is employed to draw a current of air through the mill and classifier. Control of air flow is in general controlled by a by-pass valve for air to the fan F and the valve 20. The member 27 may also be used to control the air flow by moving the same over the inlet opening of conduit 26. The velocity of the air flow through the mill is such that the fines are removed as soon as formed, thus giving a maximum amount of finely pulverized coal with a minimum power consumption. The classifier is preferably of large volume, for example at least 25% of the volume of the mill proper and the fan is preferably operated to carry a relatively large proportion of coarse material out of the rotating drum into the classifier. The classifier is so constructed that it is able to handle a very large quantity of oversize material. The main separation of the fines and oversize occurs in the chamber to the right of the baffle 29. The speed of the air flow through the classifier determines to a large extent the amount of oversize dropped by the moving stream of air and coal. The deflecting plates 27 and 30 are provided for the purpose of regulating the velocity of the air flow through the classifier by changing the length of the path over which the material passes. Assume for the purpose of illustration that deflecting plate 27 is swung to the extreme left hand position and that deflecting plate 30 is moved to its extreme right hand position. With the position of the deflecting plates as just indicated, it will be seen that a substantially straight line of flow through the classifier will be provided and that little or no separation of the oversize particles of coal will occur in the chamber to the right of baffle 29 since the direction of the moving stream has not been substantially altered. Now considering the deflecting plates as indicated in Fig. 1 of the drawing, it is clear that the direction of the air stream as well as the heavy oversize particles will be changed, and that due to this abrupt change of direction, especially in the last pass of the air and coal through the classifier, considerable, if not all, oversize will be dropped and conveyed by the screw conveyer to the mill for further treatment. The heavier particles being given a downward direction of flow, in the large chamber where the air velocity is relatively low, they will not be carried around plate 27 but will continue downwardly to the screw conveyer whereas the air stream will carry the lighter particles along to the fan. It will be seen that gravity assists in the classification.

The screw conveyer is rotated at a speed considerably higher than that of the mill because of the differences in diameter of gears 34 and 35.

60 The operation of the modified form of classifier shown in Fig. 3 is similar to that shown in Fig. 1 but is of simplified construction as regards the arrangement of baffle and deflecting plate in the first pass.

65 It will be seen that by controlling the position of the classifier plates, practically any degree of classification can be obtained. Furthermore the classifier plates vary the air flow. With the position of plate 30 shown in Fig. 1, the air is first caused to turn within the curve of this plate and thereafter it takes a further double turn. Coarse particles will fall from the air stream through the screen 39. Coarse particles striking plate 27 will be deflected downwardly onto the screw conveyer.

The positioning of the large classifier immediately adjacent the outlet of the mill permits return of a large amount of coarse material without conveying the same any considerable distance and also takes care of overflow of balls.

It will be understood that various changes in structure may be employed without departing from the spirit or scope of the invention. Suitable access doors may be provided in the wall of the classifier and other auxiliary devices will be apparent to those skilled in the art.

Having thus described my invention, what I claim is:

1. Pulverizing apparatus comprising a rotatable drum having an end trunnion providing an outlet for the drum, a classifier having an inlet member associated with said trunnion, means for withdrawing fluid from said classifier, a screw conveyor in said classifier and extending within said trunnion, a baffle providing a plurality of vertical passages in said classifier, said conveyor being situated at the bottom of said passages, and a screen at the bottom of one of said passages above said conveyor and disposed between the baffle and the drum outlet.

2. The combination with an air swept pulverizing mill of a classifier comprising a casing having vertical walls and a bottom forming a trough having inclined walls joined by a circular portion, one of said vertical walls having an opening adjacent to the bottom of said casing, the walls forming said trough extending outwardly from said opening and providing a passageway communicating with the discharge of the mill, means forming an outlet from said casing, transversely extending deflecting plates arranged in the casing providing a plurality of vertical passages between the inlet and the outlet, a screw conveyor having a diameter approximately the same as that of said circular portion located in 40 and confined to the lower part of said trough so that the upper part of the trough is unobstructed thereby, a drive shaft extending from within said mill through the upper part of said trough, the end of said shaft within said mill being 45 connected thereto so as to be rotated thereby, and means connected to the other end of said shaft for transmitting rotational movement to said screw conveyor at an increased speed of rotation.

3. Pulverizing apparatus comprising a drum having an inlet and an outlet, means for introducing material to be pulverized into the drum, a classifier having an inlet connected to the outlet of the drum, means for withdrawing pulverized material from the drum and through the classifier, a baffle in the classifier for directing the flow of pulverized material therethrough, means for adjusting the baffle so as to vary the path of flow of the pulverized material through the classifier, means for returning coarse material from the classifier to the drum, and a screen at the bottom of the baffle and above said last mentioned means and disposed between the baffle and the drum outlet.

4. Pulverizing apparatus comprising a drum having an inlet and an outlet, means for introducing material to be pulverized into the drum, a classifier having an inlet connected to the outlet of the drum, means for withdrawing pulverized material from the drum and through the classifier, a baffle in the classifier for directing the flow of pulverized material therethrough, means for adjusting the baffle so as to vary the path of flow

of the pulverized material through the classifier, means for returning coarse material from the classifier to the drum disposed below the baffle, and a screen above said last mentioned means and disposed between the baffle and the drum outlet.

5. Pulverizing apparatus comprising a drum having an inlet and an outlet, means for introducing material to be pulverized into the drum, a classifier having an inlet connected to the out-

let of the drum, means for withdrawing pulverized material from the drum and through the classifier, a baffle in the classifier for directing the flow of pulverized material therethrough, means for returning coarse material from the classifier to the drum, and a screen at the bottom of the baffle and above said last mentioned means and disposed between the baffle and the drum outlet.
